UNITED STATES PATENT OFFICE

EDWIN W. GOESER, OF LOS ANGELES, CALIFORNIA

TWO-POST THREE-SHAFT DRAW WORKS

Application filed June 27, 1928. Serial No. 288,714.

My invention relates to draw-works which are used in oil well derricks. The draw-works of this character include a line-shaft which is operated by a suitable prime mover. 5 Placed below the line-shaft is a drum-shaft, which is rotated by chain and sprocket connections to the line-shaft. The drum on the drum-shaft carries a cable which extends over the crown block of the derrick, and 10 which forms the wire cable for the crown block and traveling block which supports the drill pipe and other devices employed during the drilling of a well.

One of the objects of my invention is to 15 provide a design of draw-works which permits the use of a larger and longer spooling drum on which the cable is wound. The advantage of this arrangement is that less strains are imposed upon the cable. When 20 a cable is bent sharply, it is strained considerably. In my invention the drum is of a large diameter so that the cable is not submitted to sharp bending. Furthermore, the drum is made longer, so that it is not necessary to wind the cable layer upon layer on 25 the drum.

Another object of my invention is to provide a draw-works having two posts instead of three. The common form of a draw-works includes three posts, and between two 30 of these posts the drum is located. In my invention, by eliminating one of the posts, it is possible to make the drum considerably longer.

Another object of the invention is to provide a draw-works in which all the sprocket-chain connections between the shafts are located within the two posts. The advantage of this feature is that there will be no 35 outboard sprocket-chain connections, which are always a source of danger.

A further object of the invention is to provide a draw-works of the character mentioned, in which there are no clutches on the line-shaft. In my invention all the clutches are placed on the other shafts which are lower than the line-shaft. This is advantageous inasmuch as all of the clutch shifting mechanism may be located close to the 45 derrick floor.

A still further object of the invention is to provide a draw-works in which the drive for the rotary machine is close to the floor. The advantage of such a construction is that the chain connection is low and may be covered with a suitable guard. The guard for 55 this chain is low enough so that it does not obstruct the view in the derrick, and may be easily climbed over if necessary. This is quite an advantage over the old type of draw-works in which the chain extended diagonally downward from the line-shaft.

It is a still further object of my invention to provide a draw-works in which the rotary table may be driven without driving the 65 line-shaft or drum-shaft. The advantage of this arrangement is that wear on the draw-works is avoided, and the power which would be consumed in driving the other apparatus is saved.

It is another object of the invention to provide a shaft in which the drum-shaft is driven at a greater number of speeds than in the ordinary draw-works. This is 75 advantageous, inasmuch as the speed of the drum may be better regulated to suit the operating conditions.

A still further object of the invention is to provide a draw-works in which the line-shaft is driven by a counter-shaft at a plurality of speeds.

It is another object of the invention to provide a draw-works in which the drum-shaft is driven by sprocket-chain connections between the ends of the drum and the 85 posts of the draw-works.

A still further object of the invention is to provide a draw-works in which the two outer posts are closer together than in the ordinary draw-works.

It is an additional object of the invention to provide, in a draw-works of the character mentioned, a simple clutch-shifting mechanism.

I have briefly enumerated the predominating objects and features of the invention. In the following description of the preferred form of the invention, other objects and features will be pointed out.

In the accompanying drawings, a pre- 100

ferred form of the invention is illustrated. Referring to these drawings,

Fig. 1 is a vertical sectional view illustrating the utility of the invention.

Fig. 2 is a view taken as indicated by the arrow 2 of Fig. 1.

Fig. 3 is a view taken as indicated by the arrow 3 of Fig. 2.

Fig. 4 is a view taken in the direction of the arrow 4 of Fig. 3.

Fig. 5 is a plan view of the draw-works.

Fig. 6 is a fragmentary perspective view showing the portion of the shifting mechanism which shifts the clutches on the drum-shaft.

Referring to the drawings in detail, the numeral 11 represents the floor of the derrick. At one side of the derrick floor 11 is a draw-works 12, incorporating the features 20 of my invention. The draw-works 12 is adapted to be rotated by a prime mover indicated at 13. The draw-works is adapted to wind and unwind a cable 14, and to rotate the rotary table 15, as will be described 25 later.

Referring to Figs. 2 to 6 inclusive, the draw-works includes a pair of vertical posts 20. The lower ends of the posts 20 are secured to the floor 11 of the derrick, and the 30 upper ends are secured to a cross-beam 21 of the derrick. As shown best in Fig. 3, braces 22 extend diagonally upward from the beams 23 of the derrick, and are connected by suitable fastening means 24 to the outer edges of 35 the posts 20. The posts 20, and the braces 22, are preferably made from steel members.

Mounted on the braces 22, as illustrated best in Figs. 3 and 4, are bearing blocks 26, which rotatably support a counter-shaft 27. The counter-shaft 27 has a pair of driven-sprockets 28 and 29 rigidly secured to it by means of which it may be driven by a suitable chain 30 which is operated by a sprocket 31 or 32 of the prime mover 13. The 40 sprockets 28 and 29 are of different diameters, so that the counter-shaft 27 may be operated at two different speeds.

One end 34 of the counter-shaft 27 extends outward beyond one of the posts and 50 one of the braces, and rotatably disposed on this end 34 is a rotary table drive-sprocket 35. The rotary table drive-sprocket 35 has a rotary table drive-chain 36 extended around it, which chain also extends around 55 the rotary table driven-sprocket 37 of the rotary table 15. When it is desired to operate the rotary table 15, a clutch element 38 which is splined to the end 34, is shifted into engagement with the rotary table drive-sprocket 35, thus locking it to the counter-shaft 27, and causing it to turn therewith.

The clutch element 38 is operated by means of a yoke member 39 pivoted on a bracket 40. The yoke member 39 is resiliently retained in the position shown in Fig.

4 by means of a coil spring 41, but may be used so that the clutch element 38 engages the rotary table drive-sprocket 35 by means of a link 42, which is pivoted to the lower end of the yoke member 39. The link 42 is connected to a bell-crank 43, which bell-crank 43 is connected and rotated by a vertical link 44. As shown best in Fig. 2, the vertical link 44 is connected at its upper end to a bell-crank 45. The bell-crank 45 is 75 operated by a horizontal link 46, which horizontal link 46 is operated by a lever 47. By pulling the lever 47 in a clockwise direction, the clutch element 38 moves into engagement with the rotary table drive-sprocket 80 35, thus causing it to be driven by the counter-shaft 27.

Rotatably mounted on the counter-shaft 27 between collars 50, is a primary line-shaft drive-sprocket 51, and a secondary line-shaft drive-sprocket 52. For connecting either of these sprockets 51 or 52 to the counter-shaft 27, I provide a clutch element 54. When the clutch element 54 is swung to the left in Fig. 4, the primary line-shaft 90 drive-sprocket 51 is drivably connected to the counter-shaft 27, and when the clutch element 54 is moved to the right in Fig. 4, the secondary line-shaft drive-sprocket is drivably connected to the counter-shaft 27. 95

The clutch element 54 is moved in either direction on the counter-shaft 27 by means of a yoke member 55, which is pivoted at 56. The lower end of the yoke member 55 is connected to a horizontal link 58. The horizontal link 58 is connected to a lever 59, as shown in Figs. 3 and 4, which lever 59 is connected to a rotatable shaft 60. This rotatable shaft 60 extends forwardly to the inside of the derrick, and is bent upward in order to form an operating lever 61. The operating lever 61 is swingable to move the clutch element 54 in either direction for engaging either of the drive-sprockets 51 or 52. 100

Attached to the posts 20, near their upper ends, are bearing-blocks 64 which rotatably support a line-shaft 65. The line-shaft 65, it will be noted, is supported on the same side of the posts 20 as are the braces 22. Rigidly secured to the line-shaft 65 in alignment with the sprockets 51 and 52, are primary and secondary line-shaft driven-sprockets 66 and 67. These driven-sprockets 66 and 67 are driven by primary and secondary line-shaft drive-chains 68 and 69 respectively, which extend over the line-shaft drive sprockets 51 and 52 respectively. When the line-shaft 65 is driven through the primary line-shaft drive connections, it will rotate at one speed, and when it is driven through the secondary line-shaft driven means, it is driven at another speed. For this reason, the line-shaft 65 has two speeds to every one speed of the counter-shaft 27. Since the counter-shaft 110 115 120 125 130

27 may be driven at two speeds, the line-shaft 65 may be driven at four speeds.

Attached to the ends of the line-shaft 65 are cat-heads 70, which are used during the making and breaking of the joints of the pipe used in the well. In view of the fact that the draw-works utilizes only two posts, these posts are closer together and more in alignment with the tongs which they operate. This is a desirable feature.

10 Secured on the line-shaft 65 directly inside the posts 20, are primary and secondary drum-shaft drive-sprockets 72 and 73. These drive-sprockets 72 and 73 are rigidly secured to the line-shaft 65. It will be noted that there are no clutches on the line-shaft. This is desirable because it eliminates any overhanging clutch-mechanism.

15 Mounted on the inside of the posts 20, below the line-shaft 65, are bearing-blocks 76, which rotatably support a drum-shaft 77. The drum-shaft 77 is approximately in the same horizontal plane as the counter-shaft 27. As shown best in Fig. 2, the drum 78 20 is rigidly secured on the drum-shaft 77. At the opposite ends of the drum 78 are standard brake constructions 79. Placed on opposite sides of the drum 78, between the ends of the drum 78 and the adjacent posts 20, are primary and secondary drum-shaft driven-sprockets 80 and 81. These sprockets 80 and 81 are rotatably mounted on the drum-shaft 77. The primary drum-shaft driven-sprocket 80 is connected to the primary drum-shaft drive-sprocket 72 by a drum-shaft drive-chain 82, and the secondary drum-shaft driven-sprocket 81 is connected to the secondary drum-shaft drive-sprocket 73 by means of a drum-shaft drive-chain 84.

25 For the purpose of locking the primary drum-shaft driven-sprocket 80 to the drum-shaft 77, I provide a clutch element 85. The clutch element 85 is operated by a yoke-member 86, pivoted at 87. The yoke-member 86 is resiliently retained in the position shown in Fig. 2 by means of a spring 88. The yoke member 86 may be moved so as to cause the clutch element 85 to engage the sprocket 80 by means of a horizontal link 89 connected to the lower end thereof. The horizontal link 89 is connected to a lever 90 which, as shown best in Fig. 6, is connected to a horizontal rotatable shaft 91. This shaft 91 extends through a rotatable sleeve 92 to the forward part of the draw-works. On the inner end of the shaft 91 is connected an operating lever 93, by means of which the shaft 91 is rotated, so as to operate the mechanism which shifts the clutch element 85. As shown in Fig. 6, the sleeve 92 is rotatably supported by bearing means 95 and 96.

30 The secondary drum-shaft driven-sprocket 81 may lock to the drum-shaft 77 by means

of a clutch element 98. The clutch element 98 may be caused to engage the sprocket 81 by means of a yoke member 99, which is pivoted at 100. The yoke member 99 is resiliently retained in the position shown in Fig. 2 by means of a spring 102. The lower end of the yoke member 99 below the pivot 100 is connected to a lever 103, which is rigidly attached to the sleeve 92. The forward end of the sleeve 92, adjacent to the bearing means 95, has an operating lever 104 connected to it, by means of which the sleeve 92 may be rotated so as to operate the yoke member 99 and shift the clutch element 98.

35 In view of the two drum-shaft drive connections with the line-shaft 65, the drum-shaft will have two speeds for every one speed of the line-shaft. Therefore, since the line-shaft has four speeds, the drum-shaft 85 will have eight speeds. This is quite an advantage over the ordinary draw-works in which the drum-shaft may be driven only at three speeds. The advantage is that more speeds on the drum-shaft permit the 90 operator to more efficiently operate the drum to suit operating conditions.

40 From the foregoing description it will be seen that the draw-works of my invention is a considerable departure from the ordinary form of draw-works, which includes only a line-shaft and a drum-shaft, and not a counter-shaft; and which utilizes three posts rather than two posts, as in my invention. By utilizing only two posts it is 100 possible for the use of a longer spooling-drum, which reduces the number of layers of cable which must be wound on the drum.

45 The feature of attaching a rotary table drive-sprocket to the counter-shaft is very important to the invention in view of the fact that it permits the rotary table to be driven without operating the line-shaft or drum-shaft of the draw-works. The very important feature of the invention, of 110 course, is embodied in the use of a third counter-shaft 27, which is located close to the derrick floor. This counter-shaft is driven by the prime mover 13, and controls the operation of either the drum-shaft or 115 the rotary machine.

50 I claim as my invention:

1. In a rotary draw-works, the combination of: a pair of posts; braces for said posts; a counter-shaft rotatably supported by said braces; an operating sprocket on said counter-shaft whereby same is rotated; a rotary drive-sprocket rotatable on one end of said counter-shaft; rotary drive-sprocket clutch-means for locking said rotary drive-sprocket to said counter-shaft; line-shaft drive-sprockets rotatable on said counter-shaft; line-shaft drive-sprocket clutch-means for locking said line-shaft drive- 120

125

130

sprockets to said counter-shaft; a line-shaft rotatably supported by said posts above said counter-shaft; line-shaft driven-sprockets on said line-shaft; line-shaft chains extending around said line-shaft drive- and driven-sprockets; drum-shaft drive-sprockets on said line-shaft; a drum-shaft rotatably supported by said posts below said line-shaft; a drum on said drum-shaft; drum-shaft driven-sprockets rotatable on said drum-shaft; drum-shaft driven-sprocket clutch-means for locking said drum-shaft driven-means to said drum-shaft; and drum-shaft chains extending around said drum-shaft drive- and driven-sprockets.

15 2. A combination as defined in claim 1 in which said rotary drive-sprocket is mounted on an end of said counter-shaft which extends beyond said posts.

20 3. In a rotary draw-works, the combination of: a supporting structure adapted to be rigidly secured at one side of a derrick floor; a counter-shaft rotatably mounted on said supporting structure near the derrick floor level and having means whereby it may be driven by a prime mover, one end of said counter-shaft extending laterally beyond said supporting structure; a rotary drive-sprocket mounted on the extending end of said counter-shaft in such a position that the sprocket chain on said rotary drive-sprocket may extend to the rotary machine at one side of said supporting structure; a line-shaft rotatably supported by said supporting structure above and parallel to said counter-shaft; chain and sprocket means whereby said counter-shaft may drive said line-shaft; a drum-shaft carrying a spooling drum, rotatably supported by said supporting structure below and parallel to said line-shaft; and chain and sprocket means whereby said line-shaft may drive said drum-shaft.

45 4. In a rotary draw-works, the combination of: a supporting structure adapted to be rigidly secured at one side of a derrick floor; a counter-shaft rotatably mounted on said supporting structure near the derrick floor level and having means whereby it may be driven by a prime mover, one end of said counter-shaft extending laterally beyond said supporting structure; a rotary drive-sprocket mounted on the extending end of said counter-shaft in such a position that the sprocket chain on said rotary drive-sprocket may extend to the rotary machine at one side of said supporting structure; a line-shaft rotatably supported by said supporting structure above and parallel to said counter-shaft; chain and sprocket means whereby said counter-shaft may drive said line-shaft; clutch means for releasably connecting said chain and sprocket means which drive said line-shaft so that said line shaft need not be driven whenever said counter-

shaft is rotating; a drum-shaft carrying a spooling drum, rotatably supported by said supporting structure below and parallel to said line-shaft; and chain and sprocket means whereby said line-shaft may drive said drum-shaft.

5. In a rotary draw-works, the combination of: a supporting structure adapted to be rigidly secured at one side of a derrick floor; a counter-shaft rotatably mounted on said supporting structure near the derrick floor level and having means whereby it may be driven by a prime mover, one end of said counter-shaft extending laterally beyond said supporting structure; a rotary drive-sprocket mounted on the extending end of said counter-shaft in such a position that the sprocket chain on said rotary drive-sprocket may extend to the rotary machine at one side of said supporting structure; a line-shaft rotatably supported by said supporting structure above and parallel to said counter-shaft; chain and sprocket means whereby said counter-shaft may drive said line-shaft; a drum-shaft carrying a spooling drum, rotatably supported by said supporting structure below and parallel to said line shaft, said drum-shaft being nearly in the same horizontal plane as said counter-shaft and being interposed between said counter-shaft and the rotary machine which is driven by said rotary drive-sprocket; and chain and sprocket means whereby said line shaft may drive said drum-shaft.

6. In a rotary draw-works, the combination of: a supporting structure adapted to be rigidly secured at one side of a derrick floor; a counter-shaft rotatably mounted on said supporting structure near the derrick floor level and having means whereby it may be driven by a prime mover, one end of said counter-shaft extending laterally beyond said supporting structure; a rotary drive-sprocket mounted on the extending end of said counter-shaft in such a position that the sprocket chain on said rotary drive-sprocket may extend to the rotary machine at one side of said supporting structure; clutch-means for releasably connecting said rotary drive-sprocket to said counter shaft; a line-shaft rotatably supported by said supporting structure above and parallel to said counter-shaft; chain and sprocket means whereby said counter-shaft may drive said line-shaft; clutch-means for releasably connecting said chain and sprocket means which drive said line-shaft so that said line-shaft need not be driven whenever said counter-shaft is rotating; a drum-shaft carrying a spooling drum rotatably supported by said supporting structure below and parallel to said line-shaft, said drum-shaft being nearly in the same horizontal plane as said counter-shaft and being interposed between said counter-shaft and the rotary machine which

is driven by said rotary drive-sprocket; and chain and sprocket means whereby said line-shaft may drive said drum-shaft.

7. In a rotary draw works, a unitary supporting frame comprising uprights, a countershaft mounted in the uprights at the base thereof and adapted to be driven by a prime mover, a line shaft mounted in said uprights higher than and parallel to the countershaft, a drum shaft mounted in said uprights below and parallel to the line shaft, operative connections between the countershaft and line shaft, and between the line shaft and drum shaft, the line shaft and countershaft being on the side of the uprights opposite the drum shaft, the countershaft being extended at one end beyond the supporting frame, and having means mounted on said extension for establishing a driving connection between the countershaft and a rotary table.

8. In a rotary draw works, a derrick floor, a supporting structure rigidly secured thereto at one side thereof comprising a pair of uprights, a cross member mounted on the upper end of the uprights, braces for the uprights at the base thereof, a countershaft rotatably mounted on the braces, a sprocket on the countershaft between the braces adapted to be driven from a prime mover, an extension at one end of the countershaft beyond the supporting structure, a sprocket mounted on said extension for driving a rotary table, a line shaft mounted on the uprights above and parallel to the countershaft, a drum shaft mounted at the base of the uprights at the side opposite that on which the countershaft is mounted, sprocket connections between the countershaft and line shaft and adapted to drive the line shaft at a plurality of speeds for every speed of the counter shaft, sprocket connections between the line shaft and drum shaft and adapted to drive the drum shaft at a plurality of speeds for every speed of the line shaft, clutch connections on the countershaft and drum shaft for effecting the speed changes, all the connections between the countershaft, line shaft and drum shaft being within the planes of the uprights.

In testimony whereof, I have hereunto set my hand at Los Angeles, California, this 22nd day of June, 1928.

EDWIN W. GOESER.
